Des. 236,008
Patented July 22, 1975

236,008

AUTOMATIC TELEPHONE DIALER

Thomas G. Wixon, 1589 Blackstock Ave.,
Simi, Calif. 93065

Filed Aug. 8, 1973, Ser. No. 386,726

Term of patent 14 years

Int. Cl. D14—03

U.S. Cl. D26—14 A

FIG. 1 is a front perspective view of an automatic telephone dialer embodying my new design;

FIG. 2 is a side elevational view thereof;

FIG. 3 is another side elevational view thereof; and
FIG. 4 is a bottom plan view thereof.

I claim:

The ornamental design for an automatic telephone dialer, substantially as shown.
